FURNACE

Eberhard H. Dau, Dormont, Pa.

Application May 2, 1938, Serial No. 205,642

5 Claims. (Cl. 263—40)

This invention relates to furnaces such as used for heating metal articles and materials and, particularly, to an improved furnace for such use in which the heating chamber can be varied in size as desired.

Heretofore, in the heating of metallic articles or materials in such furnaces, it was usually necessary to heat the entire heating chamber of the furnace, no matter how small or how great the charge to be heated.

In heating small quantities of material, only that immediate vicinity of the chamber which the material occupies need be heated, but it has been necessary to heat the entire chamber in order to obtain the desired temperature to properly heat the material; which resulted in heating, unnecessarily, a large portion of the unused chamber. It would, of course, have been advantageous to make up a full load or charge before heating, in order to obtain the most efficient use of the heating gases but this was not always possible, due to the length of the materials or articles to be heated or due to the type of heat treatment required for any particular charge.

This unnecessary heating of the unused portion of the heating chamber resulted in a needless waste of fuel and increased the length of time of treating.

According to the present invention, the size of the heating chamber of such furnaces can be increased or decreased, as desired, by placing fire gates or doors at predetermined positions in the heating chamber to separate the portion of the chamber to be used for heat treating any particular charge from that portion not to be used.

It is one of the objects of the present invention to provide an improved type furnace for heating metallic articles and materials having a heating chamber which can be adjusted relative to the size of the charge or load to be heated.

It is another object of the invention to provide a furnace which will heat metallic articles and materials both efficiently and economically with a minimum amount of loss of heat and consumption of fuel.

It is a further object of the invention to provide an improved type of fire door or gate for use in furnaces which will completely seal that portion of the heating chamber to be heated and used from that portion which is not to be used.

Various other objects and advantages of this

invention will be more apparent in the course of the following specification and will be particularly pointed out in the appended claims.

In the accompanying drawings there is shown, for the purpose of illustration, one embodiment which my invention may assume in practice.

In these drawings:

Figure 1 is a horizontal section through the improved furnace of my invention;

Figure 2 is a side elevation partly in section 10 of the same;

Figure 3 is a section taken on line III—III of Figure 2;

Figure 4 is a section taken on line IV—IV of Figure 3;

Figure 5 is a section taken on line V—V of Figure 3, and,

Figure 6 is a section through part of the door and side wall of the furnace, showing a modified construction of the guide and supporting grooves.

There is shown in the drawings a conventional type furnace for heating metallic articles and materials with which my invention is incorporated. This furnace comprises side walls 2, a floor or bottom 4, a top or roof 5, a permanently closed end wall 3 at one end thereof, a movable door or gate 6 at the opposite or charging end, and an elongated heating chamber 7. A furnace of this type is usually gas-fired by means of a plurality of spaced burners 8 positioned in each of the side walls thereof, which are controlled by means of a similar number of valves 9.

According to the invention there is arranged at predetermined spaced intervals within the heating chamber on the inside of the side walls, 35 sets of oppositely disposed guide grooves 10, which are preferably beveled toward the charging end of the furnace and extend at an acute angle with the floor of the furnace and an equal number of laterally extending similarly beveled 40 grooves 12 which are aligned with the bottom end of the guide grooves 10 between the side walls. There is positioned, preferably on the top of the furnace above each set of guide grooves opposite openings 11 in the roof of the furnace, 45 a frame 13 having guide grooves carried thereby which are aligned with the guide grooves 10 of the side walls of the heating chamber for guiding and supporting a fire gate or door 14. This frame also carries preferably a pulley 15 over 50 which a chain or rope 16 is adapted to be actuated. The chain or rope is suitably connected to the top of a door and is provided for the purpose of raising or lowering the doors 14 into and out of the heating chamber 7, as desired.

The fire gate or door 14, as shown in Figures 4 and 5, comprises a heat resisting or insulating material 17, such as fire brick or, preferably, Sil-O-Cel brick, having a heat resisting metallic sheet 18 on one side thereof and, preferably, a low carbon metallic sheet 19 on the opposite side thereof, with a channel-like cast iron or heat resisting metallic frame 20 therearound. The door is constructed in this manner so as to prevent warpage thereof due to the heat. The bottom of the frame is preferably relieved toward the charging end of the furnace, as shown in Figure 4, so as to cooperate with the beveled surface of the groove 12 in the bottom of the furnace to completely seal that edge of the door. The sides of the frame are also preferably relieved toward the charging end of the furnace, as shown in Figure 5, to cooperate with the inner beveled edges of the guide grooves 10 of the side walls of the chamber to completely seal these edges when the door is in position in the heating chamber.

There is shown in Figure 6 a modified form of construction of the guide grooves in the side walls of the heating chamber. In this construction, the guide grooves are built out from the side walls of the chamber as shown, by means of fire brick pilasters 21 bound to the surface of the walls. This method of construction has the advantage over the cut-in guide grooves in that the fire brick pilasters could be easily replaced in case of damage.

It will be seen that any one of the doors 14 can be raised or lowered to lengthen or shorten the heating chamber toward the charging end of the furnace. When the doors are in position in the guide grooves 10 of the heating chamber, they are, of course, arranged at an acute angle to the floor of the chamber toward the charging end of the furnace due to the fact that the guide grooves are arranged at such an angle. Such an arrangement allows the doors to lie against the inner beveled edges of the guide grooves 10 of the side walls and the groove 12 of the floor due to their own weight, thereby completely sealing that portion of the heating chamber to be heated and used, from that portion which is not to be used. It is preferable that a gas-escapement valve 22 be positioned in the top of the furnace 30 communicating with the heating chamber enclosed by each of the fire gates so as to allow a means of escapement for the small leakage of gas through the doors from the used portion of the heating chamber to the unused portion 55 thereof, which may occur and collect in these chambers when the furnace is in use, thereby preventing the danger of explosion.

It will be understood that it would not be necessary to provide a plurality of doors but one door could be provided and moved from one position to the other as desired; and, furthermore, the doors need not be inserted from the top of the furnace as shown in the drawings but the furnace may be constructed and the doors arranged so as to slide into the heating chamber from the side thereof.

As a result of my invention, it will be seen that the burners positioned between the fire gate and a charging door at the charging end of the furnace need be used only to heat any load therein and that the burners in back of the fire door need not be used and can be closed by means of the valves 9, thereby resulting in a saving of

fuel. With such an arrangement, the size of the heating chamber can be increased or decreased, as desired, according to the size of the load or charge to be heated.

While I have shown and described an embodiment of my invention, it will be understood that this embodiment is merely for the purpose of illustration and description and that various other forms may be devised within the scope of my invention, as defined in the appended claims.

I claim:

1. An elongated heating furnace of the class described having one end thereof permanently closed and an opening in the opposite end for charging the same, and means associated with that portion of the furnace toward the closed end thereof for varying the length and size of the heating chamber therein.

2. An elongated furnace of the class described having one end thereof permanently closed and an opening in the opposite end for charging the same, a plurality of spaced apart doors associated with that portion of the furnace toward the closed end thereof, said doors being constructed and arranged so that any one of them may be positioned in said furnace so as to reduce the length and size of the heating chamber therein.

3. An elongated furnace of the class described having one end thereof permanently closed and an opening in the opposite end for charging the same, a plurality of spaced apart doors associated with that portion of the furnace toward the closed end thereof, said doors arranged substantially for vertical movement into and out of said furnace whereby the movement of any one of them into said furnace provides a predetermined sized heating chamber therein.

4. An elongated furnace of the class described having one end thereof permanently closed and an opening in the opposite end for charging the same, said furnace having a plurality of openings spaced apart at predetermined intervals and arranged in one wall thereof in that portion of the furnace toward its closed end and communicating with the heating chamber therein, and means adapted to be inserted through any one of said openings into said furnace so as to reduce the length and size of the heating chamber therein.

5. An elongated furnace of the class described having one end thereof permanently closed and an opening in the opposite end for charging the same, said furnace having a plurality of spaced apart openings arranged in the top wall thereof in that portion of the furnace toward its closed end, a set of guide grooves arranged in the side walls and floor of said furnace opposite each of said openings with the grooves in said side walls being disposed at an acute angle with the floor toward the charging end of the furnace and with each of the grooves beveled toward said charging end, and a door arranged opposite each of said openings with each of said doors having edges corresponding with said grooves so that any one of said doors may be inserted through its opposed opening into the furnace and positioned in said grooves at an acute angle so as to reduce the length and size of the heating chamber and to completely seal that portion of the chamber to be heated and used from that portion not to be heated and used.

EBERHARD H. DAU.
